BORDER STABILIZERS

Joseph Martin, Laurelton, N.Y., assignor to Eclipse Sleep Products, Inc., Brooklyn, N.Y., a corporation of New York

Filed Aug. 26, 1960, Ser. No. 52,269
10 Claims. (Cl. 5—351)

This invention relates to border stabilizers for mattresses, upholstered items, and the like, and is related to stabilizers of the class illustrated in United States Letters Patent No. 2,509,831, issued May 30, 1950, and constitutes a continuation-in-part of applications for Patent Serial Nos. 767,655 and 835,263, filed October 16, 1958, and August 21, 1959, both now abandoned.

Among the objects of the present invention it is aimed to provide a stabilizer of the class illustrated in United States Letters Patent No. 2,509,831 in which the laterally extending ends are characterized by circular loops forming the supports or abutments for the ends of a helical spring to supplement the yieldable resistance to vertical compression by yieldable resistance to longitudinal tension thereby to counteract torsional strains, that is resistance to torsional strains, and minimize the tendency to bulging.

These and other features, capabilities, and advantages of the present invention will appear from the subjoined detailed description of specific embodiments thereof illustrated in the accompanying drawings in which:

FIG. 1 is a fragmental perspective of a mattress equipped with the improved stabilizer made according to the invention disclosed in United States Letters Patent No. 2,509,831.

FIG. 2 is an enlarged side elevation of the stabilizer as shown in FIG. 1.

FIG. 3 is a section on the line 3—3 of FIG. 2.

FIG. 4 is an enlarged side elevation of a stabilizer made according to a second embodiment of the invention.

FIG. 5 is a plan view of the embodiment shown in FIG. 4.

FIG. 6 is a fragmental enlarged perspective of one end of the stabilizer shown in FIG. 4.

FIG. 7 is a section on the line 7—7 of FIG. 6.

FIG. 8 is an enlarged fragmental perspective of a third embodiment showing one end of the stabilizer.

FIG. 9 is a section on the line 9—9 of FIG. 8.

FIG. 10 is a side elevation of a stabilizer on a smaller scale than that shown in FIG. 4 of a fourth embodiment of the invention.

In the embodiment illustrated in FIGS. 1, 2 and 3, the stabilizer 1 made according to the invention disclosed in United States Letters Patent No. 2,509,831 consists essentially of upper and lower abutments, outwardly extending extensions between said abutments, and inwardly extending loops formed in the outer ends of the outwardly extending extensions. More specifically, the stabilizer 1 composed of a yieldable material such as wire or narrow flat stock is provided with two outwardly extending pairs of inclined sides 2, 3 and 4, 5, constituting outwardly extending extensions, connected to one another by the circular loops 6 and 7 respectively constituting inwardly positioned abutments such as the inwardly extending loops formed at the outer ends of said outwardly extending extensions. The lower inclined sides 3 and 5 are connected by the lower horizontally extending side 8 constituting the lower abutment which is connected by the helical connecting spring 9 to the lower border wire 10 and the upper inclined sides 2 and 4 terminate in the upper sides 11 and 12, constituting an upper abutment, which overlap and are connected to one

2

another by any suitable means such as the twists 13 and 14 and then connected by the helical connecting wire 15 to the upper border wire 16 of the mattress frame.

The sides 11, 2, 3, 8, 5, 4 and 12, constituting an endless unit, and loops 6 and 7 are part of a single resilient wire. A transverse bracing extension such as the second helical spring 17 is provided with hook formations 18 and 19 at its ends which engage the loops 6 and 7 respectively and maintain the loops 6 and 7 at a predetermined tension relative to one another determined by the cooperation of the elasticity in the spring wire of the unit 1 and the elasticity in the helical spring 17. The spring 17 thereby in turn facilitates adjusting the tension in the stabilizer either by eliminating the helical spring 17 and relying only on the rhomboid construction 1 or twisting the helix of the spring 17 more or less according to the tension required.

Excellent results have been achieved when the wire constituting the unit 1 illustrated in FIGS. 1, 2 and 3, is No. 13 gauge, of about 0.0915" in diameter and when the wire of the helical spring 17 is composed of wire No. 17 gauge of about .052" in diameter and the wire constituting the unit 1 is elliptical in shape having either a major axis of 0.120" and a minor axis of 0.080" or a major axis of 0.146" and a minor axis of 0.073", as disclosed in copending application for Patent Serial No. 766,598 filed on October 10, 1958, and executed on or about October 9, 1959, by Gustav Drews, now abandoned.

With regard to adjustment by means of the helical spring 17, attention is called to the fact that when the wire of the unit 1 is composed of high carbon steel wire No. 13 gauge of about 0.0915" in diameter and in size approximates 8" from the inner periphery of loop 6 to the inner periphery of the loop 7 of about 10½" from the outer periphery of the loop 6 to the outer periphery of the loop 7 and about 5½" from the outer periphery of the sides 11 and 12 to the outer periphery of the side 8, and the helical spring 17 in its free unstretched extent is about 8" in length, the diameter of the helix about ½" and the wire is composed of high carbon steel of about No. 17 gauge of about 0.052" in diameter, that then the load will be increased from two pounds to two and three-quarter pounds when the helix of the wire 17 is given two turns as contrasted to its free unstretched condition.

The embodiment shown in FIGS. 4, 5, 6 and 7 differs in part from the embodiment shown in FIGS. 1, 2 and 3 in that the ends of the outer wire 20 are not positioned adjacent to one of the border wires such as the border wires 10 and 16 but are formed into circular loops 21 and 22 which are disposed adjacent to one another clear of, and intermediate, the border wires 23 and 24 where they are connected to one another by any suitable means such as the rivet 25 of this embodiment or the clip 26 of the embodiment shown in FIGS. 8 and 9.

Furthermore, the stabilizer 27 of the embodiments of FIGS. 4 to 7 inclusive instead of being six-sided is substantially oval or elliptical with the intermediate substantially straight areas 28 and 29 of the wire 20 presenting a single wire for connection to the border wires 23 and 24 respectively by the helical wires 30 and 31 respectively. With this construction the diameter of the helices of the wires 30 and 31 may be reduced materially, snugly to connect the portions 28 and 29 of the wire 20 to the border wires 23 and 24 and thus prevent any unnecessary movement and consequent rattling between the wire 20 and the border wires 23 and 24 when the mattress is compressed during use.

In the embodiment shown in FIG. 10, the wire 32 is bent to form a six-sided unit such as disclosed in FIGS. 1, 2 and 3 but retaining the advantage of presenting a

single wire area to the border wires 33 and 34 and also the further advantage that the crimping of the ends of the wire 32 is obviated, the rivet 25 of FIG. 6 or the clip 26 of FIG. 8 taking the place of the crimping thereby materially reducing the cost of manufacture without impairing the efficiency of the unit.

The loops 21 and 22 of the embodiment illustrated in FIGS. 5 and 6 are disposed at one end of the elliptical stabilizer 27 with the wire 20 formed into a loop 35 at the other end of the stabilizer to enable the helical intermediate spring 36 to be connected at one end to the rivet 25 connecting the two loops 21 and 22 to one another, and at its other end to the loop 35 both within the elliptical conformation of the wire 20.

In the embodiment shown in FIG. 10, the rivet 37 is shown as connecting together the small loops at the left end of the unit 32 to one another, such as the small loops 21 and 22 of the embodiment shown in FIG. 5 and the loop 38 shown at the other end of the unit 32 to enable the helical tension spring 39 to be connected at one end to the rivet 37 and at the other end to the loop 38.

With the embodiment illustrated in FIGS. 4 to 7 inclusive the rivet 25 and loop 35 of course present the advantage of enabling the ends of the helical spring 36 to be connected inside of the elliptical formation of the wire 20. The clips 26 of the embodiment illustrated in FIGS. 8 and 9 present the added advantage that one end of the helical spring 40 may be connected directly to the loops 21 and 22 of the wire 20 and thereby not encircle an additional thickness such as the rivet 25 of the embodiment illustrated in FIGS. 4 to 7 inclusive thereby reducing the width of the unit at this point to a minimum.

The elliptical formation of the wire 20 in the embodiment illustrated in FIGS. 4 to 7 inclusive thus has two outwardly protruding extensions intermediate the border wires 23 and 24 in which extensions are formed the inwardly protruding loops 21, 22 and 35 and the six-sided unit 1 illustrated in FIGS. 1 to 3 inclusive consists of two outwardly protruding extensions between the border wires 16 and 10 having inwardly protruding loops 6 and 7 extending from the middle of each extension.

It is obvious that various changes and modifications may be made to the details of construction without departing from the general spirit of the invention as set forth in the appended claims.

I claim:

1. A border stabilizer for a mattress or the like having upper and lower border wires, said stabilizer composed of one piece of wire having upper and lower abutments, outwardly extending extensions between said abutments, inwardly extending loops formed in the outer ends of said extensions, a helical tension spring having ends connected to said loops, and means connecting said abutments to said upper and lower border wires.

2. A border stabilizer for use with a mattress or the like having an upper and a lower frame spaced from one another by hourglass springs, the upper frame having an upper border wire and the lower frame having a lower border wire, said stabilizer having upper and lower longitudinally extending abutments, means connecting said abutments to said upper and lower border wires, said stabilizer having six sides with the upper and lower sides constituting said upper and lower abutments and the remaining four sides formed into pairs, each pair of equal length forming an acute angle with one another and extending outwardly from said abutments and in turn forming obtuse angles with said abutments, said upper and lower sides being integral with its adjacent outwardly extending sides and constituting a single strand to enable said helical connecting springs snugly to engage said stabilizer, a helical spring, and inwardly positioned abutments at the acute angle of each pair of outwardly extending sides, the ends of said extension spring connected to said latter abutments, and the six sides of said stabilizer forming an endless unit composed of a resilient material

yieldable when said abutments are urged toward one another.

3. A border stabilizer for a mattress or the like having upper and lower border wires, said stabilizer composed of a single piece of a yieldable material and having ends thereof connected to one another to form an endless strip, said stabilizer having upper and lower abutments and outwardly extending extensions between said abutments, inwardly extending loops formed in the outer ends of said extensions, a helical tension spring having ends connected to said loops, and means connecting said abutments to said upper and lower border wires.

4. A border stabilizer for a mattress or the like having an upper and a lower border wire, said stabilizer being resilient and having upper and lower substantially longitudinally extending abutments, helical connecting springs connecting said abutments to said upper and lower border wires, said stabilizer having a single wire formed into outwardly protruding extensions intermediate said border wires, and inwardly protruding loops extending from the middle of each extension, means for connecting the ends of said wire to one another, and a helical tension spring connected at its ends to said loops, the ends of the wire of the stabilizer terminating clear of said border wires to enable said helical connecting springs snugly to engage a single strand of said stabilizer wire and said upper border wire, and also a single strand of said stabilizer wire and said lower border wire.

5. A border stabilizer for a mattress or the like having an upper and a lower border wire, said stabilizer having upper and lower longitudinally extending abutments, connecting means connecting said abutments to said upper and lower border wires, said stabilizer having outwardly protruding extensions intermediate said border wires, and inwardly protruding loops extending from the middle of each extension, and a helical tension spring connected at its ends to said loops.

6. A border stabilizer for a mattress or the like having an upper and lower border wire, said stabilizer having upper and lower longitudinally extending abutments, connecting means connecting said abutments to said upper and lower border wires, said stabilizer having a single wire formed into outwardly protruding extensions intermediate said border wires and inwardly protruding loops extending from the middle of each extension, means for connecting the ends of said wire to one another, and a helical tension spring connected at its ends to said loops.

7. The combination as set forth in claim 6 in which the ends of said wire terminate clear of said border wires to enable said helical connecting springs snugly to engage a single strand of said stabilizer wire and said upper border wire, and also a single strand of said stabilizer wire and said lower border wire.

8. A border stabilizer for a mattress or the like having an upper and a lower border wire, said stabilizer having upper and lower longitudinally extending abutments, connecting means connecting said abutments to said upper and lower border wires, said stabilizer having a single wire formed into six sides with the upper and lower sides constituting said upper and lower abutments and the remaining four sides formed into pairs, the sides of each pair of equal length, the sides of each pair forming an acute angle with one another and extending outwardly from said abutments and in turn forming obtuse angles with said abutments, a helical tension spring, and means at the acute angles of each pair of outwardly extending sides connecting the ends of said tension spring to said sides.

9. A border stabilizer for a mattress or the like having an upper and a lower border wire, said stabilizer having upper and lower longitudinally extending abutments, connecting means connecting said abutments to said upper and lower border wires, said stabilizer having six sides with the upper and lower sides constituting said upper and lower abutments, and the remaining four sides formed into

pairs, each pair of equal length forming an acute angle with one another and extending outwardly from said abutments and in turn forming obtuse angles with said abutments, a helical tension spring, and means at the acute angles of each pair of outwardly extending sides connecting the ends of said tension spring to said sides, the six sides of said stabilizer being composed of a resilient material yieldable when said abutments are urged toward one another.

10. A border stabilizer for a mattress or the like having an upper and a lower border wire, said stabilizer having upper and lower longitudinally extending abutments, connecting means connecting said abutments to said upper and lower border wires, said stabilizer having six sides with the upper and lower sides constituting said upper and lower abutments and the remaining four sides formed into pairs, each pair of equal length forming an acute angle with one another and extending outwardly from said abutments and in turn forming obtuse angles with said abutments, a transverse bracing extension, and inwardly ex- 15

tending loops at the acute angles of each pair of outwardly extending sides, the end portions of said transverse bracing extension connected to said loops, said stabilizer being composed of one piece of a resilient material yieldable when said abutments are urged toward one another.
